UNITED STATES PATENT OFFICE

HALSEY W. TAYLOR, OF WARREN, OHIO

COOLING APPARATUS

Application filed July 13, 1927. Serial No. 205,324.

My invention relates to apparatus for cooling liquids delivered from taps, faucets, or drinking fountains and the object of the invention in general is to provide a cooling coil of efficient design and construction which may be used advantageously within a small tank or compartment in connection with a refrigerating unit of standard construction.

In the accompanying drawing, Fig. 1 is a perspective view of a drinking fountain cabinet containing my improved cooling apparatus, and Fig. 2 is a top view of the same cabinet, on a larger scale, with the cover or top removed. Fig. 3 is a vertical sectional view longitudinally through the upper part of the cabinet on line 3-3 of Fig. 2. Fig. 4 is a vertical sectional view transversely of the cabinet on line 4-4 of Fig. 3. Fig. 5 is an enlarged sectional view vertically of the upper end of one of the end manifolds of the cooling coil.

As shown in the drawings, the invention has been applied to a drinking fountain cabinet 1 having a removable top or cover 2. An overflow bowl 3 on top 2 contains a jet, bubbler or other device 4 adapted to deliver a stream of drinking water at an inclination, or perpendicularly, into the bowl. A valve 5 is used in the present apparatus to control the discharge of water from jet 4. A cooling coil 6 made of copper pipe is connected to the body of valve 5, and this coil is confined within a rectangular receptacle or tank 7 which is lined upon its outside with cork or other insulating material 8. A refrigerating unit 9 is mounted upon one end wall of the tank, and the supporting head 10 of this unit is provided with circulating pipe connections 11 for the refrigerating medium of whatever kind or nature used. The cylindrical body of unit 9 extends horizontally into the upper part of tank 7, and loops 12 for the refrigerant depend from the body toward and into the bottom of the tank, the whole unit being usually submerged within a body of water maintained within the tank at a uniform level by an overflow pipe 13. A cooling apparatus of that general type is not broadly new, but in order to obtain efficient cooling effects and a relatively large storage capacity

of a supply of drinking water within a smaller cabinet than that used heretofore, I have devised a new and useful cooling coil 6 which is of U-shape when viewed from the top, whereby both sides and the inner end 55 of the refrigerating unit 9 are flanked and enclosed by the coil, although spaced apart therefrom. The coil is made of separate sections of pipe, each of which is bent into loop or U-shape, and these sections of pipe are 60 superposed and their open ends or extremities 15 welded to hollow upright members or manifolds 16-16'. Two such manifolds are used each having a series of reverted or return bend channels 17; and the ends of the 65 pipes are connected to the manifolds in such a manner that the several pipe sections provide a single continuous passage from a supply pipe 18 to a discharge pipe 19. Thus, supply pipe 18 connects with the upper end 70 of manifold 16, and the water passes therefrom into one end of the top or highest pipe section and thence through said section (following the sides and across one end of the tank) to the top of the second manifold 16', 75 and thence downwardly through the first reverted channel 17 to the intake end of the next pipe section immediately below the top section. The water now passes through this pipe section back to the first manifold 16 80 and thence downwardly through a reverted or return bend channel in this manifold to the next lower pipe section, and so on circuitously through all the remaining pipe sections and return bends until the water passes 85 from the bottom of the first manifold 16 into the bottom pipe section 14—which has its outlet end or discharge portion 19 bent upwardly to permit a connection to be made with the valve 5 instead of with the second manifold 16'. The refrigerating unit and the cooling coil are both submerged in water or other suitable solution in the tank, and cooling of the drinking water in coil 6 is effected by maintaining the water in the tank 90 at a relatively low temperature.

A cooling coil constructed as delineated has a relatively large storage and cooling capacity; it permits a smaller tank and cabinet to be used than heretofore; it takes up

only a narrow space within the tank; it parallels three sides of the tank and spans the inner end of the refrigerator unit; it permits easy assembly of the parts within the tank; it may be made of short pieces of pipe; the manifolds may be cast; and the cost of the entire outfit is considerably reduced compared with prior structures and practices, while the cooling efficiency is greatly increased.

10 What I claim, is:

1. A cooling apparatus, comprising a cabinet containing a water tank, a water-distributing fixture mounted upon said cabinet, a refrigerating unit extending into said tank, an overflow pipe for said tank, a water cooling and circulating coil of superposed loop shaped pipe sections extending along one side of said tank and thence across one end and back along the other side, a supply pipe connection for the upper pipe section, and a discharge pipe connection for the bottom section and said water-distributing fixture.

2. A cooling apparatus, comprising a water tank, a water-distributing fixture, a refrigerating unit extending into said tank, a water circulating coil of superposed loop shaped pipe sections extending along one side of said tank and thence across one end and back along the other side, a supply pipe connection for said coil and a discharge pipe connection for said coil and said water distributing fixture.

3. A cooling apparatus, comprising a receptacle, a refrigerating unit extending into said receptacle, a series of superposed U-shaped pipe section enclosing the free end of said refrigerating unit and connected in series at their corresponding ends, to form a continuous coil, a supply pipe connection for one end of said coil and a discharge connection for the other end of said coil.

4. A cooling apparatus, comprising a receptacle, a refrigerating unit extending into said receptacle, a series of superposed pipe sections loosely fitted into said receptacle and enclosing the extending portion of said refrigerating unit, said pipe sections having open ends, spaced apart from each other, means to connect superposed open ends of adjoining sections to form a continuous coil, and supply and discharge connections for said coil.

55 In testimony whereof I affix my signature.
HALSEY W. TAYLOR.
